STOUFFER, BROUH & BARR.

Mill Bolt.

No. 11,312.

Patented July 11, 1854.

Fig. 2.

UNITED STATES PATENT OFFICE.

JOHN STOUFFER, PETER BROUH, AND JOHN W. BARR, OF CHAMBERSBURG,
PENNSYLVANIA.

FLOURING AND BOLTING.

Specification of Letters Patent No. 11,312, dated July 11, 1854.

To all whom it may concern:

Be it known that we, JOHN STOUFFER, PETER BROUH, and JOHN W. BARR, of Chambersburg, in the county of Franklin and State of Pennsylvania, have invented a new and useful Improvement in the Process of Flouring and Bolting; and we do hereby declare that the following is a full, clear, and exact description of the same, reference 10 being had to the accompanying drawings, forming part of this specification, in which—

Figure 1 is an elevation and Fig. 2 a transverse section.

In the ordinary methods of manufacturing flour, four bushels and 25 lbs. of wheat are required in making a bbl. of superfine flour, and although there have been processes made known for making a bbl. out of a less quantity it has been found that all attempts 15 heretofore known to procure a regular run of quality, in which the bran or husk is reground with the farina have failed on account of the red cast or color given by the particles of fine bran passing through the 20 bolts, and from the regrinding all the offal the gluten has a great tendency to clog the bolt shortly after using. At the same time from the great quantity of bran in proportion 25 to the flour passed through the auxiliary mill great loss of power necessarily results, it being absolutely requisite to get up a high speed in said auxiliary mill. In using steam or water for the purpose of toughening the husk, the soluble and adhesive 30 character of the glutinous portion of the grain is also objectionable.

By our method of entirely separating the bran and the flouring particles previous to subjecting the stuffs to regrinding by passing them through the first or superfine bolt, 40 A, and then through a second one B under it we obviate this material loss of power required in one of the methods adverted to, as it is not necessary to run the auxiliary mill 45 C, at a greater speed than the first set of burs, being freed from the objection of adhesiveness of the other process.

On the reception of the ground grain, raised by elevators to the spout D, it is received in the first bolt A. All flour of superfine quality is deposited under the head of this bolt and conveyed to the packing chest by spout R, while the fine flour intermixed with specks is deposited in the screw box N 55 over the draw gates 1, 2, 3, 4, 5, 6, and con-

veyed by the bent tubes E E under and across the second bolt into the screw trough F, from whence it is conveyed and mixed with the stuffs from the first burs by the spout G, to be raised and rebolted in the 60 first bolt, at the head of which it deposits a still further quantity of S. F. flour. The specky flour having been thus rebolted, all that passes through the coarser mesh of the lower bolt B (it being covered with 65 S. F. cloth only half way) is conveyed by the open spout S, and screw trough H to the auxiliary mill C, by spout I. Under the head of the lower bolt B in the screw trough M a draw gate 7 is placed, which may be 70 opened and deliver into the screw trough F below when the flour is in quality to justify its rebolting. The brown stuff received at the tail of the bolt is delivered by screw M into the lower spout K on the end, while the 75 bran passes out by the spout L placed above it communicating directly with the lower end or tail of the second bolt B. The stuffs reground by the auxiliary mill are taken by elevators o o, exhibited in dotted line in 80 Fig. 2, to the lower bolt only, being delivered into the spout P. Any S. F. flour from them is deposited on the gate 7 at the head of the bolt B, and falling through is mixed with that passing through the several gates 85 under the bolt A.

By this improvement in the bolting process and apparatus we make an insignificant quantity of brown stuff (which is only bran ground fine) and avoid entirely the production 90 of middlings, at the same time increasing the production of superfine flour of uniform quality or brand, with good wheat a barrel being produced from four bushels to four bushels and six pounds.

The practical use of the improvement may be thus explained: When the quality of wheat justifies it and the run of the first bolt shows no specky matter mixed with the flour, all the gates 1, 2, 3, 4, 5, 6 may be 100 closed and of course the screw will deliver by spout R into the packing chest or barrel, but should the specks show under this bolt draw or open the gates 6, 5, 4, &c., in accordance with the appearance. Indifferent qualities of wheat may require nearly all the gates to be opened; but there is this advantage gained, there is not that necessity for a low grind (by which quality is sacrificed for appearance) to accomplish the end 105 110

proposed, viz. to make the most uniform quality, by which the character of the brand is sustained without loss of quantity in product of S. F. flour from the bushel of 5 grain, at the same time avoiding loss of power, and the production of middlings and offal.

Having described our improvement what we claim as our invention and desire to set 10 cure by Letters Patent is—

The arrangement of the bolts A and B, pipes E E, screw conveyer F and spout G' by means of which the specky flour first passing through the upper bolt A is rebolted by

being mixed with the stuffs (containing the 15 bran) as received from the main burs, by which the quantity of superfine flour is increased while the quality or brand is maintained, substantially in the manner set forth.

In testimony whereof we have hereunto signed our names before two subscribing witnesses.

JOHN STOUFFER.
PETER BROUUGH.
JOHN W. BARR.
